WATER COOLED DOORFRAME

Filed March 30, 1939

UNITED STATES PATENT OFFICE

2,195,538

WATER COOLED DOORFRAME

Henry Russell Loxterman, Aspinwall, Pa., assignor to Blaw-Knox Company, Pittsburgh, Pa., a corporation of New Jersey

Application March 30, 1939, Serial No. 264,929

9 Claims. (Cl. 122—499)

The present invention relates to doorframes and more particularly to water cooled doorframes for use on furnaces of various different types.

5 The present invention constitutes a substantial improvement over the prior art structures and more particularly over the structures shown in Williams Patent No. 1,580,187 and Chandler Patent No. 2,084,017. In the structures shown in 10 said patents a tubular member is provided for surrounding the furnace door and the water is circulated therethrough. The tubular header is in communication with the main circulation chamber of the frame and this main circulation 15 chamber is formed of a plurality of plates which are welded together and welded to the header surrounding the furnace opening. As shown in said patents the main circulation chamber is not independently water tight but the header surrounding the furnace opening forms a wall thereof. A number of difficulties have been encountered with structures of this character and it is the purpose of the present invention to overcome them.

25 The body section of the frame of structures of the above character is protected from the more intense heat of the furnace by the refractories and by the door. The tube section which surrounds the furnace opening is exposed to the intense heat of the furnace. The hot water, which 30 always contains impurities, causes corrosion of the walls. Furthermore this tube section is deformed or ruptured frequently due to the impact of the solid material being charged into the furnace. Of course care is ordinarily taken in the 35 operation of melting furnaces to prevent undue abuse of the frame structure during the charging operations but impacts do occur from time to time regardless of the precautions taken. The intense heat to which this portion of the frame 40 is subjected also tends to cause distortion between it and the main body of the frame and this tends to cause leaking in the weld between the tube and the main body of the frame. It will be obvious that any break in the weld between the plates forming the body section of the frame and the tube will permit leakage and such leakage will be detrimental to the hot brickwork of the furnace and will also increase the hazard 45 of liquid steel or slag explosions.

50 By the present invention I provide a structure which obviates the various difficulties mentioned above. In accordance with my invention I provide a frame comprising two independently water-tight cooling sections for the sides and top

of the door opening, one of the cooling sections being arranged to immediately surround the door opening so as to receive direct heat from the furnace and the other cooling section being 5 astride the section surrounding the door opening. The section surrounding the door opening is connected to the other section by appropriate connections so that water can be circulated through both of them. The section surrounding the door opening is in the form of a tube and is 10 preferably secured to the main body section of the frame by welds. The welding between the two need not be water-tight because the two sections are independently water-tight and any breakdown of the welds in the event that they are originally made continuous will not affect the 15 operation of the frame.

By the use of a structure such as I provide, at the expiration of the usual life of the tube portion 20 the tube may be cut away from the balance of the frame and replaced with a new tube. This materially increases the life of the total frame and cuts down operating costs. The body of the frame is not injured in any way by the cutting loose of 25 the worn tube of the frame and, furthermore, the soundness and water-tightness of the new tube installed and the body portion is not actually affected by the welding or other means employed for fastening the tube in proper position. If welding is used, only sufficient welding need be done 30 to connect the two parts with sufficient structural strength. The welding does not need to be continuous or of a water-tight character.

In the accompanying drawing I have shown for 35 purposes of illustration only a preferred embodiment and several modifications of my invention. In the drawing—

Figure 1 is a front elevation of the frame which I provide;

Figure 2 is a section taken along the line II—II 40 and showing the frame and the cooperating door in position in front of the furnace opening;

Figure 3 is a section taken along the line III—III of Figure 1;

Figure 4 is a section taken along the line IV—IV 45 of Figure 1;

Figure 5 is a partial sectional view showing a modified arrangement of the water connections between the legs of the body portion and the legs 50 of the tube;

Figure 6 is a partial elevation showing a still further type of connection between the legs of the main frame and the tube;

Figure 7 is a partial sectional view similar to Figure 4 showing a modified form of connection 55

between the tube and the water discharge pipe; and

Figure 8 is a sectional view similar to Figure 3 showing a modified form of main frame and the connection thereof with the tube.

As shown in the drawing, the doorframe which I provide embodies two independently water-tight cooling sections for the sides and top of the door opening. One of the sections, the tube 2, is arranged to immediately surround the door opening 3. The body section 4 of the frame is positioned astride the tube 2. The tube 2 is substantially U-shaped, the legs 5 extending downwardly along the sides of the furnace opening. This tube 15 is shown in the drawing as being in the form of a cylindrical pipe. It will be understood, however, that my invention is not limited to the use of a cylindrical tube and that the tube may assume any suitable configuration.

20 The body section 4 of the frame is formed of a plurality of plates which are welded or otherwise suitably secured together so as to provide an independent water-tight circulation chamber. The upper portion of the body section extends 25 over the top of the tube 2 and leg portions 6 extend downwardly along or adjacent to the legs 5 of the tube.

Appropriate connections between the tube 2 and the body section 4 are provided for circulating the cooling fluid therethrough. These connections may, of course, be arranged to circulate the water through the portions of the frame in any manner desired, the manner shown and described herein being one suitable arrangement, 35 but my invention is not limited to this or any other particular circulation of cooling water through the portions of the frame. The body section 4 has an inlet 7 and by means of this inlet and the conduit 8 connected therewith water is discharged into the body section adjacent the upper end thereof. The water flows in both directions through the upper portion of the body section and then passes downwardly through the legs 6 thereof. A conduit 9 connects the bottom 40 of each leg 6 with the adjacent leg 5 of the tube 2 so that water will be discharged from the legs 6 of the body section into the legs 5 of the tube. The water will then circulate upwardly through the tube 2 and passes therefrom through a connecting pipe 10 into a conduit 11 which is connected to the outlet 12 in the top wall of the body section. A vent hole 13 is located in the conduit 11 to permit any air which may have 45 collected in the body section to escape through the outlet opening 12.

As shown in Figures 1 and 4 the connecting pipe 10 may be joined to the conduit 11 by welding. Any other suitable form of connection may be utilized so long as the connecting pipe 10 may 50 be readily disengaged from the conduit 11 in order to permit the removal of the tube 2 from the body section of the frame when it is necessary or desirable to replace it.

In Figure 7 I have illustrated a modified form 65 of connection between the connecting pipe 10 and the conduit 11. As illustrated therein the connecting pipe 10 and the conduit 11 may be exteriorly threaded for cooperation with a standard connector 14.

70 The connections between the legs 6 of the main section of the frame and the legs 5 of the tube may assume various different forms. In Figure 5 I have illustrated a connection embodying a U-shaped conduit 15, the ends of which are 75 inserted in the adjacent legs 5 and 6 through

appropriate openings therein. Where a conduit of this character is utilized it may be welded to the side walls of the openings through which it extends.

In Figure 6 I have shown a further type of 5 connection between the adjacent legs 5 and 6 of the cooling members. In this embodiment a standard elbow coupling and union 16 is employed.

The body section 4 of the frame sits astride the tube section 2 and is secured thereto by welding or any other desirable method of holding them together. As shown in Figures 1, 2 and 3, the tube section 2 is welded to the adjacent wall 17 of the leg 6. The front plate 18 of the body section extends beyond the side plate 17 and it 15 also is welded to the tube section 2. The front plate 18 is joined to the tube section at the edge thereof which projects beyond the wall or plate 17. The welds connecting the tube 2 and the body section may extend substantially continuously 20 around the tube or the two cooling sections can be secured together only at spaced points.

In Figure 8 I have shown a slightly different method of securing the cooling members together. In this embodiment the front plate 18 and the 25 rear plate 19 of the body section are extended beyond the side plate or wall 17 and the extensions thereof are welded to the tube 2. It will be obvious that in either of these embodiments the tube 2 may be spaced a suitable distance from 30 the body section. It will also be obvious that in either of the embodiments the welds can be severed readily and the tube section separated from the body section and a new tube connected thereto.

As shown in Figure 2, the cooling member or tube 2 is located adjacent the furnace opening 3 in the furnace wall 20. This member will be subjected to the intense heat of the furnace as it is positioned between the furnace door 21 and the 40 furnace wall 20 adjacent the opening. The legs 6 of the body section and the upper portion of the body section will be protected to a substantial extent from the high furnace temperatures. The welds between the body section and the tube will 45 likewise be protected to some extent from the high furnace temperatures although in view of the independent water-tightness of the cooling members it is immaterial whether the welds hold up completely. As stated above, in the prior art 50 structures, it is absolutely essential that they withstand the temperature effects or leakage will result.

While it is not essential that the body section be cut away adjacent the connection between the 55 connecting pipe 10 and the conduit 11 as shown in Figure 1, I preferably cut the body portion away to permit ready access to the connection in order to facilitate the replacement of the tube section after it has outlived its usefulness.

It will be apparent from the above description that the structures which I provide possess the advantages referred to above, namely, replaceability of the tube section, independent water-tightness of the cooling sections, the elimination 65 of sharp corners and hence the elimination of cracking and opening up of the welds, and increased life of the total frame.

While I have shown and described preferred 70 embodiments of my invention it will be understood that I do not intend to be limited thereby and that my invention may be otherwise embodied within the scope of the appended claims.

I claim:

1. A hollow water-cooled furnace doorframe 75

comprising two independently water-tight cooling sections for the sides and top of the door opening, one of said sections being tubular and arranged to immediately surround the door opening so as to receive direct heat from the furnace and the other of said sections being positioned astride the tubular section, connections joining the two sections into a single unit, and pipe connections for circulating water through said sections from a single source of supply.

2. A hollow water-cooled furnace doorframe comprising a water-tight tubular section forming the arch of the doorframe, a water-tight body section having walls independent of the tube section, means for circulating water through both the tube section and the body section, and connections for joining the tube and body sections, such connections permitting the joining of the two sections without effecting the water-tightness of either and permitting the separation thereof without modifying the water-tightness of the body section.

3. A hollow water-cooled furnace doorframe comprising a tubular section of inverted U-shape forming the arch of the doorframe, a body section having walls forming a water-tight circulation chamber independently of the tubular section, said body section having a top portion extending over the top of the tubular section and legs extending downwardly therefrom along the legs of the tubular section, means providing a fluid connection between each leg of the body section and the adjacent leg of the tubular section adjacent the bottom thereof, and connections for circulating a cooling fluid through both the tubular and body sections.

4. A hollow water-cooled furnace doorframe comprising a tubular section forming the arch of the doorframe, a body section having walls forming a complete water-tight circulation chamber independently of the tubular section, said body section having a top portion extending over the top of the tubular section and legs extending downwardly therefrom adjacent the tubular section, means for detachably securing together the tubular and body sections, and fluid connections including connections between the legs of the body section and the tubular section for circulating a cooling fluid through the tubular section and the body section.

5. A hollow water-cooled furnace doorframe comprising a tubular section of inverted U-shape forming the arch of the doorframe, a body section having walls forming a complete water-tight circulation chamber independently of the tubular section, said body section having a top portion extending over the top of the tubular section and legs extending downwardly therefrom along the legs of said tubular section, a well of the body section conforming in general configuration with the tubular section and said wall and tubular section being welded together at spaced points along the periphery of the tubular section, means providing a fluid connection between each leg of the body section and the adjacent leg of the tubular section, and connections for circulating a cooling fluid through the tubular section and the circulation chamber.

6. A hollow water-cooled furnace doorframe comprising a tubular section forming the arch of the doorframe, a body section having walls forming a water-tight circulation chamber independently of the tubular section, the body section having a top portion extending over the top of the tubular section and legs extending downwardly therefrom along the legs of the tubular section, means providing a fluid connection between each leg of the body section and the adjacent leg of the tubular section near the bottom thereof, and connections including a conduit communicating with the tubular section adjacent the top thereof and extending through the top portion of the body section for circulating a cooling fluid through both of said sections.

7. A hollow water-cooled furnace doorframe comprising a tubular section forming the arch of the doorframe, a body section having walls forming a water-tight circulation chamber independently of the tubular section, said body section having a top portion and legs extending downwardly therefrom along the legs of the tubular section, a U-shaped conduit providing a fluid connection between each leg of the body section and the adjacent leg of the tubular section, the legs of such U-shaped conduit extending vertically upwardly in said legs, and means for circulating a cooling fluid through the tubular and body sections.

8. A hollow water-cooled furnace doorframe comprising a water-tight tubular section forming the arch of the door frame, a water-tight body section having walls independent of the tubular section, said body section having a top portion extending over the top of the tubular section and legs extending downwardly therefrom along the legs of the tubular section and having at least one wall extending beyond the main portion of the body section connected to the tubular section, means providing a fluid-tight connection between each leg of the body section and the adjacent leg of the tubular section adjacent the bottom thereof, and connections for circulating a cooling fluid through both the tubular and body sections.

9. A hollow water-cooled furnace doorframe comprising a tubular section forming the arch of the doorframe, a body section having walls forming a water-tight circulation chamber independently of the tubular section, said body section having a top portion extending over the top of the tubular section and legs extending downwardly therefrom along the legs of the tubular section and having at least one wall extending beyond the other walls of the body section and connected to said tubular section, means providing a fluid connection between each leg of the body section and the adjacent leg of the tubular section near the bottom thereof, and connections including a conduit communicating with the tubular section adjacent the top thereof and extending through the top portion of the body section for circulating a cooling fluid through both of said sections.

HENRY RUSSELL LOXTERMAN.
